DRILLING AND TAPPING MACHINE

Joseph F. Buhr, Ann Arbor, Mich.

Application January 2, 1935, Serial No. 39

17 Claims. (Cl. 77—32)

This invention relates to drilling and tapping machines and more particularly to such machines provided with mechanism for automatically providing slow feeding speeds and rapid traversing speeds.

In the machine according to this invention the traversing and feeding movement of the tool is produced by a cam. Heretofore in cam operated machines arranged for slow feeding and rapid traversing, the feeding and traversing speeds and the distances through which each operate have been produced wholly by the design of the cam. Thus for each combination of feeding and traversing and of relative distances through which each operate, a different cam has been required. The result thus was the requirement of a large supply of cams. Furthermore, when new pieces of work had to be operated on, it often happened that a new cam had to be made to retain the desired relation between feeding and traversing speeds and distances. As an example let it be supposed that in the case of the prior practice the machine was fitted with a cam for feeding at B feeding speed through X distance and C traversing speed through Y distance. Also the next job to be performed required feeding at B' speed through X' distance and C traversing speed through Y' distance. It is obvious that a new cam would be required. Corresponding cam changes also had to be made for changing from drilling to tapping, requiring a further set of cams. Clearly a complete set of cams would be infinite in number.

According to the present invention all of the above objections are eliminated by providing a cam which drives its follower at a constant speed and providing independent feeding and traversing drives, the rates of which may be independently adjusted. In addition the length of the feeding and traversing is adjustable through an adjustable dog mechanism. This construction permits great flexibility in both drilling and tapping and on any piece of work. In drilling blind holes the machine may be adjusted to continue the feeding speed after the tool has started its rearward movement and then initiate the rapid traversing movement. This adjustment results in the drilling of a clean hole without any projecting clips at the end. Also in tapping, the machine may be adjusted to back out the tapping tool at feeding speed until it has cleared the work before starting the rapid traversing.

An object of this invention is to provide a drilling and tapping machine in which the axial movement of the tool is provided by a cam and

the rate of axial movement is controlled by an automatically operated dog controlled clutch.

Another object of this invention is to provide a drilling and tapping machine where the traversing speed is superimposed over the feeding speed through the medium of an overrunning clutch.

A further object is to provide a novel starting and stopping mechanism.

Further objects reside in the combination and operation of the parts to produce a positive and efficient mechanism.

These and other objects will be apparent from the following specification when taken with the accompanying drawings in which,

Fig. 1 is a partial vertical section taken through the longitudinal central axis of the machine showing a part of the feed mechanism which is located in front of the section,

Fig. 2 is an elevation of the right end of the machine as viewed in Fig. 1 having at its center portion the covering plate and end supporting frame broken away,

Fig. 3 is a section on line III—III of Fig. 2 showing the main clutch,

Fig. 4 is a section on the line IV—IV of Fig. 2 showing the traversing control clutch,

Fig. 5 is a section on the line V—V of Fig. 1 showing the overrunning clutch connection between the feeding and traversing mechanism,

Fig. 6 is a cross-section of the overrunning clutch taken on line VI—VI of Fig. 5,

Fig. 7 is a view of a portion of the left side of the machine as viewed in Fig. 2 with the covering plate removed showing the feeding change gear mechanism,

Fig. 8 is a section on line VIII—VIII of Fig. 2 showing the stopping mechanism and the dog and clutch mechanism controlling the feeding and traversing,

Fig. 9 is a developed portion of the dog drum of Fig. 8 showing the traversing initiating and stopping dogs in position,

Fig. 10 is a section on line X—X of Fig. 9 showing the structure of a dog and the manner in which it is secured to its drum,

Fig. 11 is a fragmentary section taken on line XI—XI of Fig. 8 showing a detail of the traversing stopping mechanism,

Fig. 12 is a section on the line XII—XII of Fig. 8 showing a detail of the traversing initiating mechanism,

Fig. 13 is a fragmentary view showing a detail of the machine stopping and starting control device,

Fig. 14 is a fragmentary view of the right side of the machine as viewed in Fig. 2 showing the traversing change speed gears with their covering plate removed and an elevation of the starting and stopping control device,

Fig. 15 is a view taken on the line XV—XV of Fig. 1 showing the front end of the machine and being broken away to show the details of the starting and stopping control devices,

Fig. 16 is a view of a portion of the starting and stopping control device having the left portion as viewed in Fig. 15 broken away in part to show details of construction,

Fig. 17 is a fragmentary view showing the spindle traversing and feeding, operating head and the follower against which the main driving cam operates to axially move the spindle,

Fig. 18 is a fragmentary side view broken away in part showing details of the follower engaged by the main driving cam,

Fig. 19 is an elevation of the main operating cam for providing a constant speed stroke and return to the follower, and

Fig. 20 is a plan view of the main operating cam as shown in Fig. 19.

Referring to Fig. 1 of the drawings the machine is enclosed in a housing 1. The housing 1 is divided into two sections by a central partition 2 and is closed at the front and rear by cover plates 3 and 4, respectively. At the rear of the housing 1 and within the cover plate 4 is a supporting frame 5 in which there are mounted various shafts and pins of the machine.

Power is supplied to the machine through the main driving shaft 6 which in turn is driven by the pulley 7 keyed or otherwise suitably retained thereto. The rear end of the shaft 6 is mounted in a bearing 8 supported by the frame 5 and the front end of the shaft 6 is mounted in a bearing 9 supported in the bracket 10 comprising a portion of the housing 1.

The tool being driven is rotated by the spindle 11 and is preferably axially moved, together with the spindle 11, by the unidirectional stroke and returns endless double-end screw cam 12 continuously rotatable in one direction throughout a complete cycle of operation, having portions for providing the follower with a constant speed stroke and return. It will be observed in Figs. 19 and 20 that the cam 12 comprises two opposed helical portions 12a and 12b. Obviously, types of cams other than the double-end type may be used. Further, cams having a constant pitch over only a portion of their operative surfaces may find application within the scope of the present invention. Such a case might be where the usual traversing and feeding is done over the constant pitch stroke portion of the cam and a special axial movement of the spindle is provided by the remaining portions of the cam. The main driving shaft 6 is hollow and receives the spindle 11 to which it is splined by means of keys 13 and the axially extending slots 14.

The feeding and traversing speeds of the driven tool are determined by the speed of rotation of the cam 12. That is, for slow feeding speeds the cam 12 rotates slowly and for quick traversing speeds the cam 12 rotates relatively quickly. Power for driving the cam 12 at both feeding and traversing speeds is taken from the main driving shaft 6 through the gear 15. The gear 15 may be either formed integrally with the shaft 6, as shown, or may be secured thereto in some suitable manner as by shrinking. The gear 15 drives the gear 16 mounted on the shaft 17.

Mounted on the shaft 17 is also a gear 18 which drives a gear 19 connected to any suitable oil pump for supplying pressure lubrication to the mechanism in a manner conforming to standard practice but not shown. See also Fig. 2.

The main operating clutch including part of the mechanism for driving the cam 12 at feeding speeds is shown in Fig. 3. The gear 16, as shown in Figs. 1 and 2, drives the gear 25 shown in Fig. 3. The gear 25 is freely mounted on the shaft 26 being supported by antifriction bearings 27, and is provided with an elongated sleeve 28 having at one end thereof a toothed clutch face 29. Splined to the enlarged portion 30 of the shaft 26 for axial movement thereon is a yoke block 31 having a toothed clutch face 32 engageable with the clutch face 29. Fitting over the yoke block 31 is a yoke 33 fixed to the longitudinally slideable shaft 34. The shaft 34 is mounted in the bracket 35 comprising a portion 20 of the central partition 2 and the sleeve 36 extending from the form 5. Within the sleeve 36 is disposed a helical spring 37 maintained under compression and abutted at one end against the shaft 34 and at the other end against the cover plate 4. Normally the action of the spring 37 forces the yoke 33 to the left and the clutch including the faces 32 and 29 is disengaged. Upon the moving of the shaft 34 to the right in a manner later to be described the clutching faces 32 and 29 are engaged, with the result that the rotating gear 25, through the clutch faces 32 and 29, rotates the yoke block 31. The yoke block 31 being splined to the enlarged portion 30 of the shaft 26, rotates the shaft 26, which rotates the gear 40 keyed to it. The gear 40 meshes with the gear 41, see Fig. 1, to drive the shaft 42 and the worm 43 mounted thereon. The worm 43 is in mesh with and drives a worm gear 44 mounted on a shaft 45. The shaft 45 has mounted thereon a gear 46. See Fig. 7. The gear 46 is located in a change speed gear box 47 and is in mesh with a gear 48 mounted in the slot 49 of the fixed bracket 50. A nut 51 is arranged to take up on the headed bolt 52 to maintain the gear 48 in adjusted position in the slot 49. It is to be understood, however, that any suitable change speed gear mechanism may be used.

The gear 48 drives a gear 53 secured to the shaft 54. The shaft 54 is secured to and drives the outer cylinder 55 of the overrunning clutch 59. The overrunning clutch comprises, in addition to the outer cylinder 55, an inner cylinder 60 keyed or otherwise suitably secured to the shaft 61. In the surface of the inner cylinder 60 are cut one or more triangularly shaped notches 62, with one side extending substantially radially, each having disposed therein a cylindrical bar 63 of slightly less diameter than the depth of the notch measured at the radially extending side. Thus upon rotating the outer cylinder 55 in a clockwise direction, the cylindrical bar 63 will be wedged between the inner cylinder 60 and the outer cylinder 55, whereby when the outer cylinder 55 is rotated in a clockwise direction the inner cylinder 60 will be rotated therewith together with the shaft 61.

The shaft 61 is supported for rotation in suitable bearings 65, 66 and 67 and has secured thereto a worm 68. The worm 68 engages with and drives a worm gear 69. The worm gear 69 is keyed to and drives the rotatably mounted sleeve 70 having integrally formed thereon, or otherwise secured thereto, the cam 12 by means of which the tool supporting and driving spindle 11 is axially moved. 75

The mechanism just described for rotating the cam 12 is for axially moving the spindle 11 at feeding speed. The cam 12 is rotated at a rapid traversing speed by means of mechanism driving the gear 71 secured to the shaft 61 and located in change speed gear box 72. The traversing speed is controlled by the clutch mechanism shown in Fig. 4 and the dog and latch mechanism shown in Figs. 8 through 12.

The traversing speed mechanism receives its power from the gear 40 shown in Figs. 2 and 3 and thus is thrown into and out of operation by the engagement and disengagement of the main clutch faces 32 and 29. The gear 40 is in mesh with and drives the gear 15 shown particularly in Fig. 4. The gear 15 is mounted for rotation upon the short shaft 16 supported by the frame 5 and the bracket 77 extending from the main housing 1. The gear 15 drives the gear 18 mounted for free rotation on the shaft 19 which is supported by the bearings 80 and 81. The bearings 80 and 81 are mounted, respectively, in the frame 5 and the bracket 82 extending from the main housing 1. The gear 18 is provided with an elongated sleeve 83 having a toothed clutch face 84. The clutch face 84 is adjacent to and adapted for engagement by the toothed clutch face 85 on the yoke block 86. The yoke block 86 is splined to the enlarged portion 87 of the shaft 19 and is engaged by a yoke 88 movable in a direction parallel to the axis of the shaft 19. The yoke 88 is mounted on the axially movable rod 89. The rod 89 is slidably supported at one end in the frame 5 and at the other end in the bracket 90, see Fig. 8, extending from the main housing 1.

As viewed in Fig. 4 the left end of the axially moving rod 89 extends into a bore 91 and has threaded thereto the flanged cap screw 92. Mounted on the portion of the rod 89 within the bore 91 and bearing against the flange of the cap screw 92 and one end of the bore 91 is a helical spring 95 for normally urging the rod 89 to the left to move the yoke block 86 to engage the clutch faces 84 and 85. The axial movement of the rod 89 is controlled by the dog and latch mechanism shown particularly in Figs. 8 through 12.

Upon engagement of the clutch faces 84 and 85 the freely rotating gear 18 rotates the yoke block 86 which, being splined to the enlarged portion 87 of the shaft 19, drives the spiral gear 96 keyed to the shaft 19. The spiral gear 96 meshes with and drives a spiral gear 97 and through it the shaft 98 to which it is keyed. The shaft 98 extends laterally of the machine and into the traversing change speed gear box 72 where it has mounted thereon the gear 99. See Figs. 2 and 14. The gear 99 meshes with a gear 100 mounted on the bracket 101 pivoted about the shaft 98. The bracket 101 is provided with a slot 102 through which extends a bolt 103 passing through a bracket 104. A nut 105 is threaded to the bolt 103 and is arranged to clamp the bracket 101 in adjusted position in a manner well known in the art. The gear 100 meshes with and drives the gear 71 secured on the shaft 61. The shaft 61 is shown particularly in Fig. 5 and, as above described, has secured thereto the worm 68 and the inner cylinder 60 of the overrunning clutch 59. By changing the adjustment of the bracket 101 and the size of the gear in the change speed gear box 72 on the shaft 61 the speed of rotation of the shaft 61 may be varied in a well known manner. The shaft 61 is extended from the change

speed gear box 72 and has a squared end 110 for receiving a crank for manual traversing.

Referring to Figs. 8 through 12 wherein is particularly shown the dog and latch mechanism for operating the traversing controlling clutch shown in Fig. 4, the rotatably mounted sleeve 70 carrying the feeding and traversing cam 12 shown in Fig. 1, is extended to the rear of the worm gear 69 thereon, where it has mounted a drum 111 having two annular dovetailed grooves 112 and 113 in its surface. The drum 111 abuts at one end against the sleeve 70 supporting bearings 114 and is clamped thereagainst by the bushing 115 threaded into the end of the sleeve 70. Disposed in the annular dovetailed grooves 112 and 113 are camming dogs 118 and 119, the former being arranged for camming its follower radially of the drum and the latter being arranged for camming its follower axially of the drum. The dogs 118 and 119 are, aside from their camming surfaces, of the same construction. Each is made of two halves having flared portions extending under the edges of their respective annular dovetailed grooves. Each of the dogs is tapped to receive set screws 120 at each end, each tap having one-half disposed in opposed sections of the longitudinally split dogs. The dogs are made in two halves so that each may be inserted in its respective groove. They are secured in position by the set screws 120 bearing against the bottom of the grooves. The dogs are thus forced upwardly, their lower flared portions engaging with the sides of the grooves and binding them in position.

Briefly stated, the traversing clutch shown in Fig. 4 is operated in the following manner: The clutch operating rod 89 is axially moved to the left, as viewed in Fig. 8, against the action of the helical spring 95 by the dog 119 and is moved to the right when the dog 118 cams its follower 121 upwardly to release the detent 122 permitting the spring 95 to move the rod 89 to the right or rearwardly.

As shown in Figs. 4 and 8 the dog 119 has just engaged with its follower wheel 125 rotatably mounted on the inner end of the rod 89, thus drawing the rod 89 to the left against the action of the spring 95 opening the clutch faces 84 and 85 to stop the rapid traversing. At the same time the detent 122 mounted on the slideable block 126 resiliently pressed downwardly by the helical spring 127, is forced into the notch 128 in the rod 89 to lock the rod 89 in its left or clutch open position, after the dog 119 has moved from its position engaging its follower wheel 125. The drum 111 then continues to rotate until the dog 118 engages the follower wheel 129 on the follower 121 to lift the block 126. On the lifting of the block 126, the detent 122 secured thereto is lifted from the notch 128 thereby allowing the spring 95 to move the shaft 89 to the right, as shown in Fig. 8, to engage the clutch faces 84 and 85 (Fig. 4). As heretofore explained, the engaging of the clutch faces 84 and 85 results in the driving of the cam 12 at traversing speed. After the dog 118 has passed the follower wheel 129 and a predetermined traverse has been given to the spindle 11, depending on the relative positions of the dogs 118 and 119, the dog 119 comes into engagement with its follower wheel 125 to move the rod 89 to the left to disengage the clutch faces 84 and 85 to stop traversing. By selectively positioning the dogs 118 and 119 and by using more than one pair of them, if necessary, any combination of feeding and trav-

ersing of the tool may be obtained. The starting and stopping mechanism, which operates the main clutch, is shown particularly in Figs. 13, 14, 15 and 16. The shaft 34 carrying the yoke 33 which engages and disengages the main clutch having faces 32 and 29, see Fig. 3, is axially moved by an eccentrically disposed pin 135 supported by the rotatable shaft 136, bearing against the fork 137. The shaft 136 is supported by the main housing 1 and the pillow block 138 and is maintained against axial movement by the nut 139 and the shoulder 140. Oscillating movement is supplied to the shaft 136 by the compressed air operated piston 141. The piston 141 is disposed in a cylinder 142 and has therein helical springs 143 and 144 for urging the piston to substantially center position. The cylinder is connected to any suitable source of compressed air by a pipe 145 and controlled by button operated valves 146 and 147. The operation is such that when the button operated valve 146 is pressed, compressed air is conducted through the pipe 148 to the upper portion of the cylinder 142 to drive the piston downwardly. Release of force directed against the button operated valve 146 cuts off the supply of compressed air and permits the piston 141 to be returned to its normal position. Pressure on the button operated valve 147 admits air to the lower portion of the cylinder 142 through the pipe 149 to drive the piston 141 upwardly. Release of force directed against the button operated valve 147 cuts off the supply of air to the lower portion of the cylinder 142 and permits the piston 141 to be returned downwardly to its normal position. The piston 141 acts through a piston rod 155 on the arm 156 to give it a partial rotation in either direction depending on the movement of the piston 141. The connection between the arms 156 and the piston rod 155 is provided by the adjustably threaded spaced nuts 157 and 158 on the piston rod 155 and the fork having disk shaped arms 159 on the end of the arm 156. The disk shaped arms 159 straddle the piston rod 155 between the nuts 157 and 158 in such a manner that the movement of the piston rod 155 is imparted to the arm 156.

The arm 156 is integrally formed with or suitably secured to the casing 160 comprising approximately one-half of the starting and stopping housing 161. The casing 162 comprises the other half of the starting and stopping housing 161. Within the casing 160 is disposed a through arcuate slot 163 particularly shown in Fig. 16. Also in the casing 160 and disposed over the slot 163 but not extending all the way through the casing 160, and extending somewhat beyond the ends thereof, is a slot 164. Secured in the main housing 1 and extending therefrom in a direction parallel to the axis of the shaft 136, through the slot 163 of the casing 160 and into the slot 164 is a pin 165. The outer end of the pin 165 is squared as at 166. Extending through the squared portion 166 is a pin 167 and projecting from each end of the slot 164 and into the same are pins 168 and 169. Disposed within the slot 164 is a helical spring 170 abutting at one end against the end of the slot 164 and at the other end against the squared end 166 of the pin 165. The spring 170 is maintained in position by the pins 168 and 167. Similarly disposed on the opposite side of the squared end 166 and within the slot 164 is a second helical spring 171. The effect of the slot 163 is to limit rotary movement of the casing 160. The effect of the springs 170 and 171 is to resiliently maintain the casing 160 in a

predetermined position with respect to the pin 165. That is, should the casing 160 be rotated one way or the other, release of the rotating source will result in the springs 170 and 171 returning the casing 160 to its normal predetermined position. 5

Referring further to Fig. 16 a pin 175 is secured in the casing 160 and extends upwardly into the slot 176 in the casing 162. Thus oscillatory movement of the casing 160 which is freely mounted on the shaft 136 will move the pin 175 in the slot 176. On striking either end of the slot 176 the pin will move the casing 162 therewith. Also, secured to the casing 160 is an arm 177 for manual oscillation thereof. The casing 162 is keyed to the shaft 136 so that oscillation of the casing 160 ultimately results in a corresponding oscillation of the shaft 136 which, as heretofore explained, results in axial movement of the main clutch rod 34 by the fork 137. 20

The operation of so much of the starting and stopping mechanism as has been described is as follows: Downward movement of the arm 156, as shown in Fig. 16, will bring the pin 175 into engagement with the upper end of slot 176 with the result that the casing 162 is moved in a clockwise direction and in turn moves the shaft 136 in a clockwise direction. Referring now to Fig. 1, the rotation of the shaft 136, as viewed therein, is counter-clockwise, and the eccentric pin 135 is moved to the right to move the rod 34 to the right. This movement engages the main clutch having faces 32 and 29 and ultimately initiates feeding of traversing movement of the tool carrying and supporting spindle 11 depending on whether or not the traversing clutch shown particularly in Fig. 4 is in or out of engagement. On release of downward operating force against the arm 156 the springs 170 and 171 operate to return the casing 160 to normal position with respect to the pin 165. 30

Shown most clearly in Figs. 8 and 13 and in Figs. 14 and 16 is the mechanism for locking the casing 162, and consequently the main clutch having faces 32 and 29, in operating position. The operation of the machine as a whole is such that at the end of each complete cycle both feeding and traversing movements of the tool are stopped. This operation is initiated from a cam 180 on the surface of the sleeve 70. See Fig. 8. 45 The cam 180 is so positioned that at the end of a cycle it will engage the axially movable pin 181 slidably mounted in the main housing 1 and the cover plate 182 of the traversing change speed gear box 72. 50

Extending through the casing 162 and part way into the casing 160 is a depression 183. Disposed over the depression 183 is a latch 184 having an adjustable head 185. The latch 184 is pivoted at 186 between its ends to the bracket 187 extending from the cover plate 182 of the traversing change speed gear box 72. Pivoted at 188 to the bracket 189, also extending from the cover plate 182, is a lever 190, its pivotal point being substantially midway between its ends. At 65 one end 191 it is pivoted to the pin 181 and at the other end 192, it is pivoted to the end of the latch 184 away from its head 185. Disposed beneath the pivotal point 192 connecting the latch 184 and the lever 190 is a cylindrically shaped hollow member 195 closed at its outer end and open at its inner end, slidably mounted in the bore 196 and urged yieldably upward by the helical spring 197 bearing against the outer end of the member 195 and the bottom of the bore 196, 70 75

to maintain a yielding force against the pivotal point 192 to normally urge the latch 184 downwardly. Disposed at the lower end of the bore 196 is a vent 198 for permitting free movement of the member 195. Thus when the casing 162 moves in a clockwise direction as viewed in Fig. 16, the head 185 is yieldingly urged into the depression 183 when the lower edge 199 thereof passes it, thereby locking the casing 162 in its adjusted position. While the head 185 is out of the depression 183 and is urged against the outer face of the casing 162, it rides in an annular guiding groove 200.

Referring again to Figs. 8 and 13 it will be evident that when the cam 180 comes in position beneath the pin 181 and cams it upwardly, the lever 190 will be pivoted about the point 188 and the latch 184 will be pivoted around the point 186 to raise the head 185 from its locked position in the depression 183. The helical spring 37, particularly shown in Figs. 1 and 3, will then be free to axially move the rod 34 to open the main clutch having faces 32 and 29 to stop the rotation of the feeding and traversing cam 12.

In order to make possible the manual stopping of the feeding and traversing cam 12 at any desired time, the portion of the depression 183 within the casing 160, see Fig. 13, is provided with a sloping edge 201. Secured to the latch 184 is a camming block 202. The camming block 202 is positioned on the latch 184 so that when the head 185 is within the depression 183, it is within the portion of the depression 183 disposed in the casing 160. The latch 184 may then be lifted by camming up the block 202 by the edge 201. This may be done by pressing the button operated valve 141. Compressed air is thus admitted to the cylinder 142 driving the piston 141 upwardly. This movement, through the arm 156, rotates the casing 160 in a counter-clockwise direction as viewed in Fig. 16. The sloping edge 201 of the depression 183 then cams against the sloping face 203 of the camming block 202 and raises the latch 184 together with its head 185 from the depression 183 with the result that the main clutch having faces 32 and 29 is disengaged as heretofore described. The manual stopping may be accomplished by the arm 171 instead of by the piston 141, if necessary or desired.

The structure for transforming the rotation of the cam 12 into feeding and traversing movement in the spindle 11 is particularly shown in Figs. 1, 15, 17 and 18. Concentrically disposed within the sleeve 70 supporting the feeding and traversing cam 12 is an axially slideable quill 210. The quill 210 is spaced from the sleeve 70 by liners 211. Secured to the quill or integrally formed therewith is an attachment head 212 to which a drilling and tapping head may be attached in a well known manner. Within the head 212 the spindle 11 is mounted for rotation in the bearing 213. The spindle 11 has in the head 212 an enlarged end 214 having a shoulder 215 bearing against the bearing 213. The head 212 is designed to receive a driver for actuating the drilling and tapping head (not shown) which is bolted to the attachment head 212 in a manner well known. Disposed inwardly of the machine on the spindle 11 is a collar 216 having a set screw 217 which maintains the spindle 11 against axial movement with respect to the quill 210 so that axial movement of the quill is transferred to the spindle 11.

The head 212 is maintained against rotation and laterally moved by the rods 218 slidably sup-

ported in the end plate 3. See Figs. 15 and 17. The rods 218 are provided with shoulders 219, are threaded at their outer ends and are rigidly secured to the head 212 by the nuts 220. Axial movement is imparted to the rods 218 by the frame 221 which in turn receives movement in a direction parallel to the axes of the rods 218 by the feeding and traversing cam 12.

The frame 221 has two vertically extending arms 222 shown most clearly in Fig. 15. It is in these vertically extending arms that the rods 218 are secured by pinning or otherwise. The lower portion 223 of the frame 221 is centrally bored and is slidably mounted on a rod 224. The rod 224 is supported at one end by the front cover plate 3 and secured thereto by set screws 225. The opposite end of the rod 224 is disposed in a bore 226 in the central partition 2. Slidably mounted on the sleeve 227 extending around the rod 224 from the frame 221 is a block 228 yieldably held to the frame 221. The yieldable connection between the frame 221 and the block 228 comprises elongated screws 229 slidably mounted in the lower portion 223 of the frame 221 and threaded into the block 228, and the helical springs 230 disposed between the lower portion of the frame 221 and the heads of the screws 229.

The lower portion 223 of the frame 221 is extended in a direction parallel to the axis of the rod 222 to provide between the lower portion 223 and the block 228 a channel 231. Rotatably mounted on opposite sides of the channel 231, one in the lower portion 223 and the other at the block 228, are rollers 232 and 233 for receiving therebetween the feeding and traversing cam 12. Thus, as the cam 12 is rotated the frame 221 carrying the rods 218 is moved back and forth in a direction parallel to the axis of the tool supporting and driving spindle 11. The springs 230 are strong enough to prevent back lash and jumping at the instant the cutting tool breaks through a surface or as friction upon the tool is released, preventing hogging of drills into the work and chipping of drill lips yet permitting relative yielding between the rollers 232 and 233 to take up any wear that may occur and assure smooth traversing and feeding action. It will be clear that the curvature of the cam 12 at the points of intersection of the helical portions 12a and 12b, that is, the point at which the direction of movement of the follower is reversed, must correspond to the curvature of the rollers 232 and 233 to accommodate the rollers 232 and 233.

Viewing the machine as a whole in Fig. 1 it is noted that the main housing 1 is divided into two chambers, A by the front cover plate 3 and central partition 2, and B by the central partition 2 and the rear cover plate 4. In operation the chamber B housing the gear mechanism of the machine is filled with oil and chamber A is filled with grease. In order to maintain within the chambers A and B the grease and oil, respectively, all openings are fitted with the usual stuffing boxes and packing rings, or the like. It will also be understood that the moving parts are suitably journaled and fitted with the usual bearings if necessary. These details, however, are not part of the present invention and, therefore, are not described in full.

The operation of the machine is as follows: Power is supplied to the machine through the pulley 7 driving the hollow shaft 6. The tool supporting spindle 11 is splined within the hollow

shaft 6 for axial movement and is constantly rotated thereby. The feeding and traversing mechanism is driven from the gear 15 on the hollow shaft 6 and is stopped at the end of each cycle of operation, namely, a complete revolution of the feeding and traversing cam 12, by the cam 180 engaging the pin 181, to actuate the starting and stopping mechanism shown in detail in Fig. 16.

10 Power from the gear 15 is transferred to the main operating clutch having toothed faces 32 and 28 shown particularly in Fig. 3 by the gears 16 and 25. The gear 40 is driven from the gear 25 when the main clutch is engaged. Both the 15 traversing and feeding drives are taken from the gear 40. The feeding drive comprises the gear 41 in mesh with the gear 40, the worm 43, the worm gear 44 and the shaft 45 to the change speed gear box shown in Fig. 7, and thence to the shaft 54 on 20 which is mounted the overrunning clutch 59 shown in Fig. 5. The traversing drive is taken from the gear 40 by the gears 75 and 78 to the traversing clutch shown in Fig. 4, and the gears 96 and 97 to the gear 99 in the change speed gear 25 box 72 shown in Fig. 14. A connection is therein made by gears 100 and 71 to the shaft 61, the latter also being connected to the overrunning clutch 59. The manner in which the overrunning clutch operates has been clearly described 30 and therefore is not repeated. The spindle 11 is moved axially with feeding or traversing speeds depending on the rate of rotation of the cam 12. Thus while the spindle 11 is traversing the cam 12 rotates at a higher rate of speed than when it is 35 feeding.

The machine according to this invention is changeable from drilling to tapping by making appropriate changes and adjustments which will be apparent to one skilled in the art.

40 Having thus described my invention what I claim and desire to secure by Letters Patent is:

1. A machine of the character described comprising a tool carrying spindle mounted for axial and rotative movement, means to rotate said spindle, and mechanism for providing said spindle with a slow feeding movement and a rapid traversing movement, said mechanism including a sleeve continuously rotatable in one direction through a complete cycle of operation surrounding said spindle, a cam extending around said sleeve and connected thereto, means controlling the movement of said cam, and yieldable means operatively connected to said spindle and operated by said cam.

5. 2. A machine of the character described comprising a tool carrying spindle mounted for axial and rotative movement, means to rotate said spindle, and mechanism for providing said spindle with a slow feeding movement and a rapid traversing movement, said mechanism including a sleeve continuously rotatable in one direction through a complete cycle of operation surrounding said spindle a cam extending around said sleeve and connected thereto, means connected to said spindle and operated by said cam, an overrunning clutch, a feeding drive connected to said overrunning clutch, a traversing drive connected to said overrunning clutch, means for operating said cam from said traversing drive, and means for clutching said traversing drive into and out of operation whereby when said traversing drive is clutched out of operation the same is driven through said overrunning clutch at feeding speed and when said traversing drive is

clutched into operation the same is rotated at rapid traversing speed.

3. A machine of the character described comprising driving means, a rotatable and axially movable tool carrying spindle splined therein, an axially movable quill concentrically disposed around said spindle and secured to said spindle for axially moving the same, a rotatable sleeve concentrically disposed around said quill, a feeding and traversing cam secured to and coaxial with said sleeve, means to rotate said sleeve at feeding and traversing speeds, and a connection between said cam and said quill for imparting to said quill, feeding and traversing axial movement, said cam being characterized by the fact that it is continuously rotatable in one direction through a complete cycle of operation and that the movement imparted by it to the quill is at a constant rate both stroke and return.

4. The invention as defined in claim 3 wherein the connection comprises yieldable means.

5. The invention as defined in claim 3 wherein the connection comprises a slidable frame including a yieldable follower.

6. In a machine of the character described, the combination of a rotatable and axially movable spindle, means to rotate said spindle and mechanism for axially moving said spindle, said mechanism including a rotatable double end cam, a follower for said cam, and means connecting said follower to said spindle, said follower comprising two yieldably engaged members spaced apart to form a channel for receiving said cam.

7. In a machine of the character described, the combination of rotating means, a tool carrying spindle mounted for axial and rotative movement splined in said rotating means and mechanism for providing said spindle with feeding and traversing axial movement, said mechanism comprising a traversing shaft, an operative connection between said traversing shaft and said spindle for providing the same with feeding and traversing axial movement, an overrunning clutch connected to one end of said traversing shaft, driving means forming a driving connection between said overrunning clutch and said rotating means, traversing means forming a driving connection between said rotating means and said traversing shaft, a main clutch in said driving means and a traversing clutch in said traversing means whereby the main clutch in the driving means controls both the feeding and traversing, and the traversing clutch controls the traversing only.

8. In a machine of the character described, the combination of a tool carrying spindle mounted for axial and rotative movement, means to rotate the spindle, means including a clutch to axially move said spindle at traversing speed, and mechanism for controlling said clutch, said mechanism comprising a rotatable drum, an axially slid able rod contiguous with the surface of said drum, a clutch operated by said rod, a dog secured to the surface of said drum for moving said rod in axial direction, means for positively locking said rod in axially adjusted position, and a second dog for releasing said locking means, whereby said traversing drive is clutched into and out of operation.

9. In a machine of the character described comprising a tool carrying spindle mounted for axial and rotative movement, means to rotate said spindle, and mechanism for providing said spindle with slow feeding movement and rapid traversing movement, said mechanism including a sleeve surrounding said spindle, a cam con-

tinuously rotatable in one direction throughout a complete cycle of operation having a constant pitch screw stroke portion extending around said sleeve and connected thereto, means connected to said spindle and operated by said cam, an overrunning clutch, a feeding drive connected to said overrunning clutch, a traversing drive connected to said overrunning clutch, a traversing drive connected to said overrunning clutch, means for operating said constant pitch cam portion from said traversing drive, and means for clutching said traversing drive into and out of operation whereby when said traversing drive is clutched out of operation the same is driven through said overrunning clutch at feeding speed and when said traversing drive is clutched into operation the same is rotated for rapid traversing speed.

10. In a machine of the character described the combination of a rotatable and axially movable spindle, means to rotate said spindle, and mechanism for axially moving said spindle, said mechanism including a rotatable unidirectional stroke and return double end cam continuously rotatable in one direction throughout a complete cycle of operation having a constant pitch screw stroke portion, a follower for said cam, and means connecting said follower to said spindle, said follower comprising two relatively yieldable members spaced apart to form a channel for receiving said cam.

30. 11. In a machine of the character described, the combination of a rotatable and axially movable spindle, means to rotate said spindle and mechanism for axially moving said spindle, said mechanism including gear mechanism, a rotatable unidirectional stroke and return double end cam continuously rotatable in one direction throughout a complete cycle of operation having a constant pitch screw stroke portion, a follower for said cam, said follower comprising a frame, 40 a block yieldably connected to said frame and adjacent thereto, defining a channel with said frame for receiving said rotatable cam, means supporting said follower for movement parallel to the axis of said spindle, and means connecting said follower to said spindle said cam bearing against the frame side of said channel to move said spindle in a forward direction and against the block side of said channel to move said spindle in a return direction.

50. 12. In a machine of the character described, the combination of a rotatable and axially movable spindle, means to rotate said spindle and mechanism for axially moving said spindle, said mechanism including gear mechanism, a rotatable unidirectional stroke and return double end cam continuously rotatable in one direction throughout a complete cycle of operation having a constant pitch screw stroke portion, a follower for said cam, said follower comprising a frame 60 mounted for movement parallel to the axis of said spindle, an extension on said frame, a block connected to said frame, slidably mounted on said extension being yieldably urged toward said frame and defining a channel with said frame, anti-friction means on opposed sides of said channel for engaging said rotatable cam, and means supporting said spindle for movement parallel to the axis of said spindle and means connecting said follower to said spindle said cam bearing against the frame side of said channel to move said spindle in a forward direction and against the block side of said channel to move said spindle in a return direction.

70. 13. A machine of the character described comprising a housing, a partition in said housing

dividing the same into front and rear compartments, a front wall for said housing, a sleeve journaled in said rear compartment, a quill journaled in said front compartment, a spindle splined to said sleeve and journaled in said quill, 5 said quill and spindle projecting through said front wall, and mechanism for reciprocating said quill, said mechanism comprising means driven by said sleeve in said rear compartment, a cam in said front compartment driven by said means, 10 a follower for said cam, and means projecting through said front wall connecting said follower to said quill outside of said front wall.

14. A machine of the character described comprising a housing, a partition in said housing 15 dividing the same into front and rear compartments, a front wall for said housing, a sleeve journaled in said rear compartment, a quill journaled in said front compartment, a spindle splined to said sleeve and journaled in said quill, said 20 quill and spindle projecting through said front wall, and mechanism for reciprocating said quill, said mechanism comprising means driven by said sleeve in said rear compartment, and a cam in said front compartment driven by said means, 25 for reciprocating said quill.

15. A machine of the character described comprising a housing, a compartment in said housing having front and rear walls, a sleeve journaled in said walls, a quill coaxial with said sleeve and slidably mounted therein, a spindle journaled within said quill and coaxial therewith, an endless cam mounted on said sleeve and coaxial therewith, a follower for said cam, a connection between said follower and said quill to reciprocate said quill, and means to rotate said sleeve 30 and spindle.

16. A drilling machine comprising a rotatable tool spindle, means for rotating said spindle, a reciprocable carriage structure having a fixed 40 forward and return stroke in which said spindle is supported for rotation and reciprocation toward and from the work piece, a cam follower connected to said carriage for reciprocating the same, a cam to which said follower is geared for 45 imparting both forward and return movement to said carriage, means for positively driving said cam in one direction throughout a complete cycle of operation and during the complete forward and return movement of said carriage, said cam being continuous with a constant pitch screw 50 portion for the forward stroke and a constant pitch screw portion for the return stroke, means for controlling and regulating the speed of rotation of said cam rotating means so as to selectively impart to said carriage both feeding and rapid traversing speeds while said follower is traversing one of said constant pitch screw portions of said cam whereby a multiplicity of various movements as to feed and rapid traversing 55 may be imparted to said carriage without change in shape and construction of said cam.

17. A drilling machine comprising a rotatable tool spindle, means for rotating said spindle, a reciprocable carriage structure having a fixed forward and return stroke in which said spindle is supported for rotation and reciprocation toward and from the work piece, a cam follower connected to said carriage for reciprocating the same, a cam to which said follower is geared 70 for imparting both forward and return movement to said carriage, means for positively driving said cam in one direction throughout a complete cycle of operation and during the complete forward and return movement of said carriage, 75

5 said cam being continuous with a constant pitch screw portion for the forward stroke, means for controlling and regulating the speed of rotation of said cam rotating means so as to selectively impart to said carriage both feeding and rapid traversing speeds while said follower is travers-

ing said constant pitch screw portion of said cam whereby a multiplicity of various movements as to feed and rapid traversing may be imparted to said carriage without change in shape and construction of said cam.

JOSEPH F. BUHR.

CERTIFICATE OF CORRECTION.

Patent No. 2,093,546.

September 21, 1937.

JOSEPH F. BUHR.

It is hereby certified that error appears in the printed specification of the above numbered patent requiring correction as follows: Page 4, first column, line 38, for the word "arms" read arm; and second column, line 34, for "of" first occurrence, read or; and that the said Letters Patent should be read with these corrections therein that the same may conform to the record of the case in the Patent Office.

Signed and sealed this 26th day of October, A. D. 1937.

(Seal)

Henry Van Arsdale,
Acting Commissioner of Patents.
